(57) **CLAIM**

We claim the ornamental design for a track lighting fixture, as shown and described.

DESCRIPTION

FIG. 1 is a bottom-rear perspective view of a decorative track lighting fixture rotated to a downward position.

FIG. 2 is a right-rear perspective view of the fixture of FIG. 1 rotated to a downward position.

FIG. 3 is an exploded view of the fixture of FIG. 1 showing a bottom-rear perspective view of a housing of the fixture of FIG. 1 rotated to a downward position and with a cap and bulb removed.

FIG. 4 is a top-left perspective view of the fixture of FIG. 1 rotated to a front-facing position; and,

FIG. 5 is a rear plan view of the fixture of FIG. 1 rotated to a front-facing position.
